UNITED STATES PATENT OFFICE

142,683

DESIGN FOR A CLOTHESPIN

Earnest C. Yeager, McGregor, Tex.

Application July 19, 1945, Serial No. 120,813

Term of patent 7 years

(Cl. D17—6)

To all whom it may concern:

Be it known that I, Earnest C. Yeager, a citizen of the United States of America, residing at McGregor, in the county of McLennan and State of Texas, have invented a new, original, and ornamental Design for Clothespin, of which the following is a specification, reference being had to the accompanying drawing, forming part thereof.

The drawing is a perspective view of a clothespin showing my new design.

I claim:

The ornamental design for a clothespin, as shown.

EARNEST C. YEAGER.
